UNITED STATES PATENT OFFICE.

ERNEST CLEFF, OF FAIRHAVEN, ASSIGNOR TO THE PAIRPOINT MANUFACTURING COMPANY, OF NEW BEDFORD, MASSACHUSETTS.

DESIGN FOR A CASKET-HANDLE EAR.

SPECIFICATION forming part of Design No. 25,060, dated January 21, 1896.

Application filed December 2, 1895. Serial No. 570,857. Term of patent 7 years.

To all whom it may concern:

Be it known that I, ERNEST CLEFF, a citizen of the United States, residing at Fairhaven, in the county of Bristol and State of Massachusetts, have invented and produced a new and original Design for Casket-Handle Ears, of which the following is a specification, reference being had to the accompanying drawings, in which—

Figure 1 is a top plan, and Fig. 2 a side, view of my new ear.

The leading feature of my design consists in a knurl forming part of the ear and at the base thereof an extension forming the remainder of the ear, the knurl and extension being ornamented, as shown.

A is the knurl, which forms part of the ear,

and B is the extension at the base of the knurl, forming the remainder of the ear. The knurl may be and is ornamented with scrolls a , ²⁰ bosses a' , and leafwork a^2 and the extension with bosses b and scrollwork b' and b^2 .

What I claim is—

The design for a casket handle ear, substantially as described.

In testimony whereof I have signed my name to this specification, in the presence of two subscribing witnesses, on this 29th day of November, A. D. 1895.

ERNEST CLEFF.
